UNITED STATES PATENT OFFICE.

ARTHUR L. WILDE, OF WETHERSFIELD, CONNECTICUT, ASSIGNOR TO PRATT & WHITNEY COMPANY, OF NEW YORK, N. Y., A CORPORATION OF NEW JERSEY.

GEAR-TOOTH GRINDER.

Application filed January 8, 1924. Serial No. 684,120.

This invention relates to a new form of machine for grinding the tooth curves of gears.

An object of the invention is to provide a machine and method which will permit grinding of tooth curves on gears of different types and sizes which will be simple and efficient in its operation.

More particularly it is an object of the present invention to provide a semi-automatic machine to carry out the method of grinding gears disclosed and claimed in the copending application of Maag 677,842 filed November 30, 1923.

15 The above objects are accomplished by means of mechanism permitting a blank to be rolled through a predetermined limited distance past one or more abrasive wheels, returned to its initial position without rolling action, and repeatedly rolled and returned. The rolling action is made substantially equal to or slightly greater than the circular pitch of the gear being ground. Mechanism is also provided for slowly 20 changing the relative position of the gear to the abrasive wheel or wheels during its rolling movement so that the entire contour of each tooth is engaged and abraded by the action of the wheel or wheels.

25 Another object of the invention is to provide simple mechanism for accomplishing this rolling and returning movement of the blank, these means comprising a master gear on the work spindle corresponding in diameter and number of teeth to the gear being ground. Means also are provided to cause the master gear to be engaged and disengaged from a precision rack in timed 30 relation to the rolling and returning motions of the gear blank and master gear. The rolling motion takes place with the master gear in mesh with the precision rack and with the gear blank in contact with the wheel or wheels. The return movement which 35 takes place without rolling occurs when the master gear is out of mesh with the rack and the gear blank entirely clear of the wheels.

40 In grinding gear teeth heretofore it has been the practice to roll a gear back and forth past a wheel or pair of wheels through the entire distance that its teeth contact with the wheels. Between each, or a succession of rolling movements, the gear is indexed, 45 after which the rolling motion is repeated.

In the present invention, the gear is not rolled through a distance sufficient to engage the abrasive wheel over the entire active contour of a tooth but the rolling motion is restricted to a distance equal substantially to its 50 circular pitch. Also, the rolling movement occurs in one direction only, the return movement taking place without rolling so that the gear blank is indexed to a new position each time it passes the abrasive wheels. 55 While these rolling and return motions of the gear are taking place, which can occur at a high rate of speed, the blank is gradually advanced laterally of the wheels so that the rolling and return motions occur in 60 successively advanced positions. As soon as this advancing movement has reached a predetermined amount, determined by the contact line of the gear, a retrograde movement is given to the blank. The rolling and 65 return movements are continued during this retrograde movement until the blank is rolled past the wheel in exactly the same path as at the beginning of the grinding operation.

70 It has also heretofore been the practice to effect a rolling motion of the blank being operated on and extend this rolling motion laterally sufficiently to permit indexing. This is usually done by rolling far enough 75 to one side to completely disengage the wheel or wheels from the work so that the blank may be indexed by special mechanism while in that position. This added rolling motion however is sufficient to materially increase the time of the grinding operation 80 and so materially reduce the efficiency of the machine.

85 In the present invention the rolling motion is limited to a distance equal to the circular pitch of the gear being ground, which can take place at relatively high speed. Indexing of the gear is preferably accomplished by withdrawing the gear directly 90 from the wheel or wheels at the end of each of a series of rolling movements and returning it to its initial position without rolling. The gear is therefore moved bodily in 95 a closed path of limited extent and, while in engagement with the wheel or wheels is being rolled to generate the tooth curves on the blanks.

100 In the present invention, no special indexing mechanism for the gear blank is required for the reason that the rolling move- 105

ment in one direction and the return movement in the opposite direction without rolling or rotative motion indexes the blank through the space of one tooth each time.

5 The mechanism may therefore be used for grinding gears having any numbers of teeth without the necessity of any special indexing mechanism.

A principal object of the invention is 10 therefore to provide simple mechanism to actuate the work blank in a manner to effect the above cycle of operations.

With these and other objects in view, my 15 invention consists in the features of construction and operation set forth in the following specification and illustrated in the accompanying drawings.

In the accompanying drawings annexed hereto and forming a part of this specification, I have shown my invention embodied in a spur gear grinding machine but it will be understood that the invention can be otherwise embodied and that the drawings are not to be construed as defining or limiting 25 the scope of the invention, the claims appended to the specification being relied upon for that purpose.

In the drawings:

Figure 1 is a plan view of the principal 30 portions of a machine made in accordance with the present invention.

Fig. 2 is a sectional view taken on line 2-2 of Fig. 1.

Fig. 3 is a vertical sectional view of the 35 principal actuating mechanism for the gear blank taken upon line 3-3 of Fig. 1.

Fig. 4 is a plan view of the mechanism for moving the master gear into and out of contact with the master rack, this view being 40 taken substantially on line 4-4 of Fig. 3.

Fig. 5 is a plan view of the master gear showing its position relative to the master rack, this view being taken on line 5-5 of 45 Fig. 3.

Fig. 6 is an enlarged view of a master gear in engagement with its rack showing the different positions of the master gear at different periods of the cycle of operations.

In the above mentioned drawings, I have shown but one embodiment of the invention which is now deemed preferable, but it is to be understood that changes and modifications 55 may be made within the scope of the appended claims without departing from the spirit of the invention.

Briefly, my invention in its broadest aspect comprises the following principal parts: first, a base preferably having a column thereon; second, swinging arms supported by means of said column; third, a work spindle rotatably mounted at the free end of said swinging arms; fourth, a master gear on said work spindle; fifth, a rack

fixed to said base and adapted to be engaged by the master gear on the spindle; sixth, a slide carrying the actuating mechanism for the master gear and other parts on said spindle; seventh, means to slowly reciprocate said slide so that the relative position of the master gear and rack is continuously changed; and eighth, one or more abrasive wheels adjustably mounted on the base.

Referring more in detail to the figures of the drawings, I provide a base 10 having secured thereto a column 11. This column, as shown, is provided near one end of the base and on one of its sides has mounted thereon attaching means for swinging arms 12 and 13. These arms 12 and 13 are in every way analogous to those disclosed in the copending application of Tanner and Knowles, Serial No. 621,307 filed Feb. 26, 1923, so that the method of attaching and supporting them does not require further explanation.

At the free end of these swinging arms is a suitable bearing for a vertical work supporting and rotating spindle 14. This spindle 14, at its upper end preferably is provided with a center 15 in alignment with an adjustable center 16 supported from the upper portion of the arm 13 so that a work arbor 17 may be supported between them. The work spindle 14 is provided also with a brake band 18 permitting a slight frictional engagement between itself and a portion of the spindle so that the work spindle 14 may be prevented from freely rotating but may be adjusted so that its driving members may rotate it positively and without lost motion or back lash.

On the work spindle 14 is a master gear 20, means being provided to readily remove it and replace it with other master gears of different sizes and numbers of teeth. Below the master gear 20 is a ball bearing 21 or other annular member adapted to contact with a vertical plane surface 22 positioned adjacent a rack 23. For convenience, the rack and the plane vertical bearing surfaces are mounted on a removable member 24 secured to the base 10 (see Fig. 5) permitting them to be readily dismounted and replaced with other racks 23 of different pitch and adapted to coact with master gears 20 of different diameters.

From the above, it will be seen that a work blank W suitably mounted on the centers 15 and 16 provided on the work spindle 14 may be rolled by suitably moving the work spindle 14 while the master gear 20 is in contact with the rack 23. It is during a rolling motion of this type that the abrasive action occurs by contact with the tooth flanks on the blank W with abrasive wheels 25, two of which are preferably used. As the abrasive wheels 25 may be mounted on wheel heads 25^a substantially similar to

those described in the above mentioned co-pending application, further description will be unnecessary. It will be sufficient to state that adjustments are provided for 5 moving the wheel heads 25^a so that the wheels 25 may be correctly positioned relative to the tooth flanks of the blanks, so that teeth of proper form may be generated. As shown in Fig. 1, the wheels 25 of suitable 10 size are positioned to engage opposite sides of adjacent teeth on the blank W and are placed in adjacent spaces of the work blank. These wheels 25 engage the teeth flanks of the blank W upon surfaces normal to the 15 axis of the spindle upon which they are rotated.

In order to cause the work spindle 14 to move in a direction to engage the master gear 20 with the rack 23 and so bring the 20 work blank W into contact with the abrasive wheels 25, the following mechanism is provided: A vertical cam shaft 26 is provided preferably rotated by a worm 27 and worm wheel 28 shown in Figs. 3 and 4. This cam 25 shaft 26 as shown in the drawings is mounted on a horizontally movable slide 29. This shaft 26 near its upper portion is provided with two cams 30 and 31. The first cam 30 is in the form of a plate having a rim 32 30 of irregular contour extending from one side surface about a portion of its periphery. This cam portion 32 is adapted to contact with a roller 33 or other member mounted on a member in the form of a bell crank 35 34 so that with each rotation of the shaft 26 the bell crank 34 is oscillated back and forth. This bell crank 34 also is mounted on the slide 29 so that it moves therewith. The other cam 31 on this shaft 26 is in the 40 form of a disc, the periphery of which is suitably shaped, and engages a roller 35 mounted in alignment with the lower end of the work spindle 14. A link 36 pivotally attached to one arm of the bell crank 34 45 rounds a ball bearing 37 on the spindle 14 and serves to support the roller 35. In order to maintain the roller 35 in contact with the disc cam 31 on the shaft 26, a spring actuated rod 40 is attached to the link 36 and 50 normally forced in a direction to hold the link 36 toward the cam 31. The effect of this latter cam 31 is to cause the work spindle 14 to move in a direction parallel with the rack 23, this movement taking place 55 while the master gear 20 is in engagement therewith so that the work spindle 14 is rotated, which causes a rolling motion of the master gear 20 along the rack 23. The first mentioned cam 30 mounted on the shaft 26, 60 which engages the roller 33 on the bell crank 34 serves to oscillate this bell crank 34 and also reciprocate the link 36. The work spindle 14 by reason of this mechanism is moved in a direction normal to the rack 23 so that 65 the master gear 20 and rack 23 are alter-

nately engaged and disengaged. The cams 30 and 31 are so placed on their shaft 26 that the movement of the parts occurs in the desired sequence or cycle.

The resultant or combined movements induced by this above described mechanism is a short rolling movement of the master gear 20 and work blank W while the master gear 20 engages the rack 23 and while the spindle 14 is being moved in one direction. At 70 that point of the cycle of operations, the first cam 30, by engaging the roller 33 on the bell crank 34, causes the master gear 20 to be disengaged from its rack 23 and the second cam 31 then returns the work blank 80 W to its initial position by a movement longitudinally relatively to the rack 23 without any rotation of the spindle 14. The first cam 30 then permits the work spindle 14 to move toward the rack 23 so that the master 85 gear 20 again engages it whereupon the cycle is repeated.

The length of rolling motion of the master gear 20 is governed entirely by the shape of the disc cam 31 and for that purpose this 90 cam is made readily removable so that others having slightly different forms may be accomplished. The first cam 30 is made of such a shape that it moves the spindle 14 in a direction normal to the rolling movement sufficiently to completely disengage 95 any master gear 20 from its rack 23. In carrying out the invention in its preferred form, the rolling motion of the master gear 20 is made substantially equal to or slightly greater than the circular pitch of the gear W before being ground. As the wheels 25 are disposed directly above the rack 23 they engage and abrade the teeth of the gear blank W while the master gear 20 engages the rack 100 23 and is being rolled therealong.

The work spindle 14 is held toward the rack 23 positively and therefore the position of the blank W relative to the abrasive wheels 25 is limited by the roller 21 on the spindle 14 engaging the vertical bearing surface 22 adjacent the rack 23. In order to resiliently hold the work spindle 14 and the mechanisms movable therewith toward the rack 23, the bell crank 34 is provided with a spring pressed rod 42 normally forced in 110 one direction. The cam projection 32 does not extend entirely about the entire periphery of the plate 30. The ball 33 is therefore not continuously engaged by this cam. 115 While the roller 33 is not engaged by the cam 32, the bell-crank 34 is held resiliently by the tension of rod 42 toward the guiding surface 22 and rack 23. The work spindle 14 is therefore held resiliently toward the 120 wheels 25 by the arm 36 being forced in that direction by rod 42 through its attachment to the bell-crank 34.

The above described mechanism is sufficient to move the work spindle 14 a short 130

distance past the wheels 25 in opposite directions and to repeatedly perform this rolling operation with the work blank W in successive rotative or indexed positions so that different tooth flanks are presented to the wheels 25. By means of the brake 18 placed on the spindle 14, the friction between it and the arm 13 carrying the spindle 14 is sufficient to prevent rotation of the spindle 14 and blank W while the master gear 20 is disengaged from the rack 23.

It is well known that a tooth stays in contact with a meshing gear tooth or with the tooth of a rack while the gear is being rolled through a distance greater than the distance represented by its circular pitch. If, therefore, the gear W were merely rolled through the distance represented by its circular pitch while it engages the wheels 25, the contour of its flanks would not be completely ground. I therefore provide means for advancing the work spindle 14 and the mechanism movable therewith longitudinally along the rack 23. This mechanism I prefer to actuate very slowly so that it is reciprocated a short distance during the complete grinding operation of a gear. For this purpose, I mount the parts above mentioned on the slide 29 in the base 10 and mount the bell crank 34 above referred to pivotally thereon. Also the support for the cam shaft 26 above referred to is provided in this slide 29. In order to actuate the slide 29, a small crank 44 is provided having a connecting rod 45 one end of which is fixed to the slide 29 and the other end of which is attached to the crank 44 which may be adjusted to any distance from its axis of rotation. By means of a suitable worm 46 and worm wheel 47, this crank may be very slowly rotated. One rotation of this crank 44 preferably takes place after a large number of rotations of the first mentioned cam shaft 26, and during the complete grinding operation of a gear W.

The cam shaft 26 may be rotated by means of the worm 27 which engages the worm wheel 28 mounted on its lower end. The worm 27 is formed of suitable length to engage the worm wheel 28 throughout the movement of the slide 29 during the entire grinding operation. This worm 27 as shown in Fig. 4, is mounted on the main driving shaft 48 of the machine. Driven from this main driving shaft 48 through suitable speed-reducing gears 49 is the shaft having the worm 46 thereon. This worm 46 is in mesh with the worm wheel 47 on the vertical shaft adapted to rotate the crank 44 at a very slow speed.

What I claim is:

1. A gear tooth grinding machine comprising in combination, means to effect a rolling motion of a blank past a grinding wheel through a limited distance, cam means

controlling said blank to successively roll said blank past said wheel in different indexed positions, and a slide carrying said actuating means movable in the direction of the rolling motion.

2. A gear tooth grinding machine comprising in combination, means to effect a rolling motion of a blank past a grinding wheel in one direction through a limited distance, means to return said blank to its initial position without rolling whereby said blank is indexed for its next rolling movement, said means being mounted on a slide, and means to move said slide in the direction of the rolling motion.

3. A gear tooth grinding machine comprising in combination, means to effect a rolling motion of a blank past a grinding wheel through a limited distance, means to move said blank into and out of contact with said wheel, and cam means controlling the movements of said blank, said cam means being mounted on a slide movable in the direction of the rolling motion.

4. A gear tooth grinding machine comprising in combination, means to effect a rolling motion of a blank past a grinding wheel through a limited distance, means to disengage the blank from the wheel at the end of each rolling movement, means to return said blank to initial position, means to re-engage said blank with said wheel, and cams for controlling the movements of said blank in the above named cycle.

5. A gear tooth grinding machine comprising in combination, means to effect a rolling motion of a blank past a grinding wheel through a distance substantially equal to its circular pitch, means to disengage the blank from the wheel at the end of each rolling movement, means to return said blank to initial position, means to re-engage said blank with said wheel, said means being mounted on a slide whereby said blank may be moved in the direction of the rolling movements during operation.

6. A gear tooth grinding machine comprising in combination, means to effect a rolling motion of a blank past a grinding wheel through a distance substantially equal to its circular pitch, means to disengage said blank from the wheel at the end of its rolling movement, means to return said blank to its initial position and simultaneously index the blank, cams to actuate said means, means to rotate said cams at the same speed, and means to advance said blank in the direction of the rolling motion during its rolling movement.

7. A gear tooth grinding machine comprising in combination, means to effect a rolling motion of a blank past a grinding wheel through a limited distance, a master gear moving with said blank in axial relation therewith, a fixed rack adapted to be en-

gaged by said master gear, cam means controlling said blank and master gear to successively roll them past said wheel in different indexed positions, and a slide carrying said actuating means movable in the direction of the rolling motion.

8. A gear tooth grinding machine comprising in combination, a base, an abrasive wheel adjustably mounted thereon, a blank supporting and rotating spindle adapted to be moved in any direction while its axis is maintained always in parallel positions, means to effect a rolling movement of a blank on said spindle past said wheel, and means to move said spindle to engage and disengage said blank with said wheel, both of said means being mounted on and moving with a slide whereby a feeding movement of said blank may be effected.
10. A gear tooth grinding machine comprising in combination, a base, an abrasive wheel adjustably mounted thereon, a blank supporting and rotating spindle adapted to be moved in any direction while its axis is maintained always in parallel positions, means to effect a rolling movement of a blank on said spindle past said wheel, and means to move said spindle to engage and disengage said blank with said wheel, both of said means being mounted on and moving with a slide whereby a feeding movement of said blank may be effected.
20. 9. A gear tooth grinding machine comprising in combination, a base, an abrasive wheel adjustably mounted thereon, a blank supporting and rotating spindle adapted to be moved in any direction while its axis is maintained always in parallel positions, means to effect a rolling movement of a blank

on said spindle past said wheel through a distance substantially equal to its circular pitch, and cam means to move said spindle to engage and disengage said blank with said wheel, both of said means being mounted on and moving with a slide whereby a feeding movement of said blank may be effected in the direction of the rolling movement.

10. A gear tooth grinding machine comprising in combination, a base, an abrasive wheel adjustably mounted thereon, a blank supporting and rotating spindle adapted to be moved in any direction while its axis is maintained always in parallel positions, means to effect a rolling movement of a blank on said spindle past said wheel, and means to move said spindle to engage and disengage said blank with said wheel, both of said means being mounted on and moving with a slide whereby a feeding movement of said blank may be effected, and crank and connecting rod means to move said slide in the direction of the rolling movement.

In testimony whereof, I hereto affix my signature.

ARTHUR L. WILDER.
